UNITED STATES PATENT OFFICE.

NOAH S. EDENS, OF HIGHLAND, CALIFORNIA.

TIDE-MOTOR.

953,600.

Specification of Letters Patent. Patented Mar. 29, 1910.

Application filed March 5, 1909. Serial No. 481,263.

To all whom it may concern:

Be it known that I, NOAH S. EDENS, a citizen of the United States, residing at Highland, in the county of San Bernardino and 5 State of California, have invented new and useful Improvements in Tide-Motors, of which the following is a specification.

This invention relates to wave and tide motors, the object of the invention being to 10 provide a simple and efficient construction of apparatus which will receive the impact and lifting power of the waves and the swell of the tides of a river, ocean or sea and convert their forces into mechanical energy in such 15 a form as to be readily and economically utilized.

A further object of the invention is to provide an apparatus of this character which will compress air for storage and use, which 20 is not liable to be injured under ordinary conditions and will, to a large extent, compensate for variations in the roughness of the water to prevent the transmission of undue strain to its working parts, and, which, 25 when the water is very rough, as in the case of a severe storm, may be readily thrown out of operation.

With the above and other objects in view, the invention consists in the novel construction, combination and arrangement of parts 30 as herein fully described, illustrated and claimed.

In the accompanying drawing:—Figure 1 is a vertical section through the lower portion of the apparatus. Fig. 2 is a similar view through the upper portion of the same. Fig. 3 is a detail view of the rod connection between the head of the motor shaft and piston of one of the compressors.

40 Referring to the drawings, 1 designates a pier, wharf or other suitable supporting structure, having an opening 2 for the upward passage of an upright motor shaft or axle 3, which is of suitable length according 45 to the power of the motor and preferably tapers uniformly toward its upper end. The lower end of the shaft is threaded to receive a nut 4, upon which rests a washer 5 against which bears the lower flanged end of a sleeve 50 6, which terminates below the top of the pier and is free for upward sliding movement on the shaft. Journaled upon the sleeve is a motor comprising a hollow chamber or float 7, preferably formed of metal and having a 55 hemispherical upper portion and a fluted

lower portion, the flutes providing a series of pockets or concavities 8 contracting the base portion of the float and extending outwardly and upwardly on proper arcs to provide curved impact faces against which the 60 waves and currents of the body of the water in which the float is immersed are adapted to strike, so that irrespective of the direction of motion of the waves or currents, either lateral or vertical motion will be communicated 65 thereby to the float, so that the applied power in either case may be utilized. The inner curved walls of the pockets or concavities also provide surfaces against which the impulse of the water from the rising and 70 falling of a stream influenced by tides will affect a vertical movement of the float and shaft, whereby motion of the water in any direction may be converted into working energy. The lower contracted portion of the 75 float is filled with a suitable ballasting material 9, acting by gravity to maintain it in a more or less erect position at all times.

The float is free for an easy revoluble movement on the sleeve 6, so that it may 80 turn to prevent injury to the apparatus in case there should be a dangerous swirl or maelstromic action of the water around or in the vicinity of the same. Flanges 10 and 11 hold the float from upward or downward 85 displacement on the sleeve, and to the flange 11 of said sleeve are pivoted dogs 12 having inwardly curved upper ends to engage recesses 13 in the shaft to normally hold the sleeve and float against upward movement. 90 The locking ends of the dog are connected by links 14 with a collar 15 encircling the shaft, from which collar rods, ropes or cables 16 extend upwardly through the opening 2 in the support to a point above the 95 same for convenient manipulation to adjust the collar up and down and thereby, through the action of the links, throw the dogs into and out of locking position. By an upward pull, the dogs will first be released and the 100 float may then be elevated a safe distance above the surface of the water to prevent injury to the apparatus during violent storms or when the water is exceptionally rough.

105 A power storer or generator is operated by the action of the float under the influence of the water and comprises an air compression apparatus, from which the air may be pumped into a suitable storage tank and em- 110

ployed to drive a dynamo or other machinery. Said power storer or generator comprises a supporting frame formed of a series of rods or standards 17 extending upwardly from the pier or wharf 1 and united by armed brackets, heads or spiders 18 and 19 and an armed crosshead or traveler 20, arranged above the lower head 19 and having its arms provided with eyes slidably engaging the rods. The body portion of the said crosshead or traveler forms a bearing for the upper end of the shaft and is provided with an opening 21 for the passage of said shaft, the lower end of said opening being flared, as at 22. Secured to the upper surface of the body portion is a cap plate 23 having a central opening 24, the walls of said openings 21 and 24 forming a curved seat or socket for the reception of a partially spherical head or journal 25 on the shaft, whereby the shaft and traveler are connected for vertical movement in unison, while the shaft is free to turn about its axis and move laterally in any direction, thus providing a practically universal point bearing to permit the shaft to have these movements without binding. Clamped upon the upper end of the shaft between a collar or flange 26 and a nut 27 is a coupling head comprising a bottom plate 28 and a top plate 29 detachably secured thereto. This head is connected with the arms of the traveler by a series of coiled springs 30. These springs are annularly arranged around the upper end of the shaft and yieldingly resist the rotary movement of the shaft in either direction. By this means the shaft is permitted to turn to a necessary degree to compensate for any twisting strain falling thereon, but is prevented from turning to such an extent as to strain or damage the pump mechanism. The plate 28 is provided at its outer edge with semicircular seat recesses 31 and the plate 29 is provided with flaring openings 32 registering with said recesses.

Arranged between and supported by the heads or spiders 18 and 19 is an annular group of main compressor cylinders 33 inclining inwardly and upwardly in compact form, said cylinders being disposed for operation in pairs, the cylinders of each pair being provided in the upper portions of their adjacent faces with slots 34 and having at their lower ends discharge nipples 35. In the lower portion of each cylinder operates a piston 36, whose rod 37 extends upwardly and is connected by a cross bar 38 with the piston rod of the companion cylinder, said bar moving in the slots 34, whereby the pistons of each pair of cylinders are coupled to operate in unison. Disposed above the cylinders 33 is an annular group of auxiliary cylinders 39 which also incline inwardly and upwardly in compact relation and are supported at their lower ends by the

head 18 and connected at their upper ends by a crown piece 40. These cylinders 39 are arranged for individual coöperation with each pair of the cylinders 33, each cylinder 39 having its lower end, open and arranged between the upper ends of the associated pair of cylinders 33, and being provided at its upper end with a discharge nipple 41. In each cylinder 39 works a piston 42 whose rod 43 extends downward through the open end thereof and is connected with the cross bar 38, which thus couples all three pistons for synchronous operation. Discharge pipes in practice may lead from the nipples 35 and 41 to a tank in which the air supplied from the compressors may be stored for use, or provision may be made for supplying the air direct to the apparatus to be driven. The cross bars 38 are connected to the coupling head of the shaft 3 by rods 44 each threaded at its lower end, as at 45, to adjustably receive a threaded sleeve 46, provided with a ball or rounded portion 47, the upper end of each rod being formed with a similar ball or rounded portion 48. The sleeves 46 of the series of rods work in the flared openings 32 in the upper plate 29 of the coupling head, while the rounded portions are fitted to articulate in the sockets formed between the two coupling head plates 28 and 29 by the seats 31 and walls of the openings 32, by which the rods are attached to the coupling head for universal pivotal motion. The rounded portions of the upper ends of the rods seat in semicircular recesses 49 in angular bosses or bearing portions 50 formed on the cross bars 38, which bosses are externally threaded to receive internally threaded retaining caps 51, each having an opening 52 flared at its outer end and communicating at its inner end with a semicircular recess 53, the recesses 49 and 53 forming a socket in which the rounded portion 48 of the associate rod articulates, whereby the rods are attached to the respective cross bars for universal pivotal motion. It will be seen that provision is made for adjusting the rods as to length and adjusting the balls within the sockets to compensate for wear and operate with greater or less freedom, and that the rods are adapted to move both vertically and laterally.

As the float rises and falls with the tide, waves or currents, it will be apparent that the shaft 3 will be reciprocated vertically, and that as a consequence motion will be transmitted through the connecting rods to reciprocate the pistons within their cylinders, whereby charges of compressed air will be on the working strokes of the pistons discharged through the nipples and into the storage tank or proper portion of the machine connected therewith. Any action of the water on the float which vibrates or moves the float laterally will also vibrate

the shaft, and in this operation the coupling head will tilt or cant the coupling head and thus operate certain of the pistons in alternation with the others. If the float is both moved vertically and laterally by the water, the rods will compensate for such movements and, as in the case of lateral motion solely, reverse some of the pistons on their working stroke and some on their return stroke. It will then be apparent that provision is made for utilizing and converting into mechanical energy the forces resulting from any and all the motions of the water from winds, tides and other causes, and that this is accomplished by adapting the float to have what might be called universal motion and adapting the parts operated thereby to compensate for such motion. If the float should be subjected to the action of a swirling current, it will simply rotate on its axis and thus prevent injury to the remaining parts of the apparatus, while, if any of this rotary motion should be transmitted to the shaft, such motion of the shaft will be limited by the springs whereby injury in this event to the power generator or storer will be prevented. When the motion of the water is very violent, as during a storm, the float may be elevated as before described to prevent damage to the apparatus and lowered again after the water is sufficiently calmed.

From the foregoing description, taken in connection with the drawings, the construction and mode of operation of my improved wave and tide water motor will be readily understood and appreciated, and it will be seen that a type of apparatus is produced which may be operated in an economical manner.

Having thus described my invention what is claimed as new, is:—

1. A motor of the character described embodying a float having a fluted lower portion forming pockets or concavities and a contracted intermediate space and ballasting material in said spaces.

2. A motor of the character described including a rod or shaft, a float slidably mounted on said shaft, locking means for securing the float in operative position to the shaft, and means for retracting said locking means and elevating said float.

3. A motor of the character described including a rod or shaft, a float slidably and rotatably mounted on the shaft, locking means for holding the float from sliding movement in operative position while permitting rotary movement thereof, and means for retracting said locking means and elevating the float.

4. A motor of the character described including a rod or shaft, a float slidably and rotatably mounted on the shaft, pivoted locking dogs for securing said float against

sliding movement, and means for retracting said dogs and elevating the float.

5. A motor of the character described including a rod or shaft, a sleeve slidably mounted thereon, a float journaled for rotation on said sleeve and adapted to slide therewith, means for locking said sleeve to the shaft, and means for retracting said locking means and elevating said sleeve and float. 75

6. A motor of the character described comprising a support, a rod or shaft mounted for rotary vertical reciprocatory and lateral pivotal movements on said support, a float carried by the rod or shaft, means for yieldingly resisting rotary movement of the shaft, a power generator, and a universally jointed connection between said rod or shaft and generator. 80

7. A motor of the character described comprising a frame, a rod or shaft mounted for vertical and lateral movements on the frame, a float for imparting motion thereto, a group of pump cylinders, pistons operating therein, and rods pivotally connecting said rod and pistons. 85

8. A motor of the character described comprising a frame, a shaft mounted for vertical reciprocatory and lateral pivotal movements on the frame, a float for operating the same, a series of compression cylinders, pistons operating in cylinders and connected in multiple, and rods pivotally connecting said shaft with the groups of multiply connected pistons. 95

9. A motor of the character described comprising a frame, a shaft mounted for vertical reciprocatory and lateral pivotal movements on said frame, a main group of compressor cylinders having pistons operating therein and connected in multiple, a group of auxiliary compressor cylinders having pistons operating therein and connected with the pistons of the main group, a float for operating said shaft, and rods pivotally connecting the shaft with said multiply connected pistons. 100 165

10. A motor of the character described comprising a support, a rod or shaft mounted for vertical reciprocatory movement and lateral pivotal movement on said support, a float slidably mounted on said rod or shaft, locking means for holding the float in normal position, means for releasing said locking means and elevating the float, and a power generator operated by the vertical and lateral movements of the shaft. 115

11. A motor of the character described comprising a vertically and laterally movable rod or shaft, a float slidably and rotatably mounted thereon, locking means for holding the float in normal working position, means for releasing and elevating the float, a power generator having a reciprocating member, and a connection for recip- 125 130

roating said member under the vertical and lateral movement of the rod.

12. A motor of the character described comprising a frame, a rod having a sliding pivotal connection with the frame, a float carried by the rod, a group of power generators having reciprocating elements, a head carried by the rod, jointed connections between the said reciprocating elements and

the head, and controlling springs connecting 10 said head with the frame.

In testimony whereof I affix my signature in presence of two witnesses.
